UNITED STATES PATENT OFFICE.

CLARENCE H. WILKES, OF GLOVERSVILLE, NEW YORK

POST-TYPE SEWING MACHINE.

Application filed December 16, 1922. Serial No. 607,380.

This invention relates to sewing machines of the post type, used principally for the sewing of gloves.

The object of the present invention is to 5 provide a practical post type machine embodying twin lock stitch mechanisms in combination with one or more cover thread mechanisms. Other objects of the present invention relate to the various parts of the 10 machine and to combinations of parts as more particularly pointed out in the claims.

The invention in its broadest aspect may be considered as an improvement on the machine described in my previous Patent No. 15 1,049,430, dated January 7, 1913, which is the first and as far as I know the only practical post type machine embodying a lock thread. The machine illustrated in my former patent is satisfactory as far as the 20 work done by it is concerned, but is incapable of sufficiently high speed to permit its being used in rivalry with the usual type of modern sewing machines, due not only to its excessive length of throw but also to 25 several other details of construction.

In the present machine great advantages are obtained by reversing the relative positions of needle bar and shuttle as shown in my earlier patent and in the re-designing of 30 the mechanism so as to permit of the use of a plurality of cover threads which in themselves aid in the locking of the seam to prevent raveling.

In the drawings I have illustrated the 35 construction of my sewing machine as it is now being used, and in which,

Figure 1 is a side elevation of the machine viewed from the right hand side.

Fig. 2 is a similar view but viewed from 40 the left hand side.

Fig. 3 is a plan view.

Fig. 4 is a front elevation of the forward parts of the machine, the cam mechanism in the rear being omitted for the sake of clear- 45 ness.

Fig. 5 is a side view of the shuttle mechanism with all of the several parts in place.

Fig. 6 is a similar view but with the shuttle race latch raised and the shuttle and 50 its driver removed to expose to view the presser foot and guide.

Fig. 7 is a vertical section taken on the line 7—7 of Fig. 1.

Fig. 8 is a vertical section partly in front elevation illustrating the shuttle drive. 55

Fig. 9 is a horizontal section partly in plan of the mechanism shown in Fig. 8.

Fig. 10 is a perspective view of one of the shuttle drivers, the pinion being omitted to expose the shaft. 60

Fig. 11 is a perspective view of the lower portion of the presser foot mechanism.

Fig. 12 is a front elevation of the twin needle thread tension.

Fig. 13 is a side view of the needle bar 65 and feed showing the parts as they appear when the feed has moved to the rear limit of its travel at which time the twin needles are entirely within the post.

Fig. 14 is a similar view but showing the 70 feed at its forward limit of travel and lowered and the needle bar in its highest position.

Fig. 15 is a perspective view of the needle bar unit. 75

Fig. 16 is a horizontal section taken through the needle bar just below the bed of the machine illustrating principally the needle bar and feed connections.

Fig. 17 is a plan view of the top of the 80 post.

Fig. 18 is a perspective view showing two pieces of fabric being united and illustrating the position of the parts at the moment of emergence of the twin needles, the ends of 85 the bobbin threads being shown moved at an angle in order not to confuse the illustration of the loopers.

Fig. 19 is a similar view but showing the 90 needles in their highest position.

Fig. 20 is a perspective view of the completed seam.

Referring particularly to Fig. 1, the machine includes a rectangular housing 10 enclosing the various cam mechanism, this 95 housing 10 being supported on the bed 11 and in turn supporting the thread holding standard 12 on which are mounted in the usual manner the needle thread spools 13 and 14 and the two looper thread spools 15. 100

From the housing 10 extends forwardly the sewing machine arm 17 carrying, instead

of the usual needle bar mechanisms, the shuttle mechanisms and also the loopers, the needles in this machine reciprocating within the stationary post 20 rising from the front of the bed of the machine.

The post 20 is conveniently formed of two similar members 21 secured together in any preferred manner as by the rivets 22 (Fig. 13) and the two members 21 are then secured within the circular flange member 24 which fastens the post to the bed. The post sections as best seen in Fig. 17 are generally L-shaped in their upper portion not quite meeting one another, so as to form a forwardly facing slot 26 in the flat front face of the post.

With the exception of the present machine, all post type sewing machines have round front faces. The advantage, however, of the flat front face is very material as the operator is enabled to guide the fabric with much greater ease over the flat front post, enabling her to make a perfectly straight seam which with the present type post in use is seemingly quite impossible. A guiding partition member 27, T-shaped in cross section, is inserted between the two sections 21 of the post and serves a dual function, namely, to hold together the two sections of the post and to act as a guard for the two needles.

The feed, contrary to the usual custom, in the present invention consists in an elongated bar 30 having a central slot 31 forming the pivotal support of the feed, a pin or other pivotal means 32 passing through the two sections of the post and forming the fulcrum for the feed. The upper end of the feed bar is serrated at the top as at 29 to form the usual feed and is recessed slightly as at 33 in order to clear the partition 27.

At its lower end the feed bar 30 carries a lug 34 serving as a seat for the spring 35 and also for a connection to the link 36 pivoted at its other end to the plunger 37. This plunger 37 is guided within the cylindrical bore 38 of the block 39 by means of a pair of bearings; the forward one of which, 40, is fast to the block while the rear bearing 41 is fast to the plunger itself. A spring 42 is loosely mounted on the plunger 37 between the stationary bearing 40 and the sliding bearing 41 and tending at all times to hold the thimble end 44 of the plunger against the feed push lever 45.

Adjustment of the threaded thimble 44, which is locked in place by a lock nut 47 alters the throw of the feed to govern the length of the stitch. The feed push lever 45 as best seen in Fig. 1 is a bell crank lever pivoted on the stationary shaft 49 and having at its upper end 50 an elongated face 51 to be engaged and operated by the pear-shaped feed cam 52. The mechanism just described at each revolution of the main power shaft

55, by the depression of the face 51, rocks the bell crank lever 45, reciprocates the plunger 37 and through the link 36 rocks the feed about its pivot 32, but does not raise and lower the feed.

The means for raising the feed includes a lever 57 pivoted to the plunger block 39 as at 58 having at one end a stirrup 60 underlying the lug 34 and at its free end being connected by a link 62 adjustably secured to the cam follower 64 pivoted on the stationary shaft 49 which extends through the housing 10. The cam follower 64 is provided with a centrally positioned slotted lug 67, a screw and bolt connection 68 passing through the link 62 and lug 67 so that the height of the throw of the feed may be altered to compensate for wear of the serrated teeth 29 and also and more particularly to facilitate the handling of the various qualities of fabric, a very low feed being required for example with silk, while certain particular grades of soft leather require a very high feed. At each revolution of the drive shaft 55 the pear-shaped cam 65 oscillates its follower 64 which transmits motion through the link 62 and the centrally pivoted lever 57 to the lower end of the lug 34 thereby raising the feed bar 30 on its fulcrum 32 which motion is readily permitted by reason of the pivoted link connection 36 between the reciprocating plunger 37 and the feed.

As the feed is entirely retracted and in its forward and lowest position the flat edge 69 of the upper portion of the feed bar is exactly parallel to the flat front edge of the post 20 and remains so while the needles rise to their highest point and throughout the movement of the shuttles. As the needles are retracted within the post the lever 57 is operated and raises the feed against the tension of the spring 35 and while the feed bar is so raised the plunger 37 is projected forward to bring the flat edge 70 of the lower portion of the feed bar into exact parallelism with the flat front face of the post.

Depending from the front edge of the bed 11 is a bracket 75 serving as a support for the standard 76 on which slides a sleeve 77 pivoted to the needle unit 78 by means of a screw 79 or other quick detachable connection. A spring 80 connects hook 81 on the enlarged end 82 of the needle unit and a hook 83 on the bottom of the bracket 75 tending to hold the sleeve 77 steady in its reciprocating movement on the standard 76. The needle unit 78 in addition to its enlargement 82 consists in a relatively long thin bar 85 grooved as at 86 and having a thread eye 87 at a point near the bottom of the rod 85 and preferably quite near the bore 88 through the enlargement 82.

The needles 89 and 90 are exactly alike and are of standard manufacture. They

are twins in every respect as I very much prefer to replace both needles in case that one should become broken. This is obviously not necessary, but it tends very strongly 5 to improve the looks of the work. The needles 89 and 90 may be secured to the holder or needle unit bar 85 by means of a set screw or in any other similar way, but my preference is to sweat the needles into 10 place obviating all difficulties that might occur with the use of tiny set screws. In practice I find it convenient to replace an entire needle unit by unscrewing the fastening 79 and to let the needle units accumulating 15 late until quite a number are to be re-needed.

Mounted in hangers 93 on the bed 11 beneath the housing 10 is a stationary shaft 94 on which is pivoted the hub 96 of a bell 20 crank lever having two substantially equal and relatively long arms, the vertical one of which, 97, carries at its upper end a roller 98 engaging the groove of the face cam 99 on the main shaft 55 while the horizontal 25 arm 100 operates the needle unit by means of mechanisms best seen in Fig. 1.

The arm 100 at its forward end is reduced and cylindrical as at 101 snugly fitting within the bore of the plunger casing 30 102, the latter being pivoted directly to the sleeve 77 preferably by means of a screw pivot such as 103. Rotation of the main power shaft 55 causes the bell crank lever 97—100 to oscillate so as to cause the needle 35 bar unit to rise rapidly to the highest point of its movement, to dwell there while the loops in the needle threads are passed over the shuttles, and then to retract the needles rapidly to their lowest position, holding 40 them stationary there during a slight period while the feed mechanism is at its highest point.

In its general form the shuttle mechanism 45 is entirely of well known elements, save for the associated mechanisms for spacing the two shuttles apart and in the combination of the shuttles with the other parts of the mechanism, and hence requires no detailed description.

50 Referring particularly to Figs. 5, 6 and 10, the shuttles are of the shuttle-hook type having a main body 110 having a hook 111 and to which is fastened a bobbin holder 112 having the usual lip and screw connection so as to hold the bobbin 114 in place. This shuttle and its driver 115 are in every 55 way of the old and well known type, the driver having a shaft 116 to which is secured in any semi-permanent manner, as by the pin 118, a drive pinion 119 meshing with the rack 120.

The eccentric 122 centrally mounted on 65 the main power shaft 55 reciprocates the shaft 124 having bearings in the front and back walls of the housing 10 and being

linked at its forward end to a pivoted yoke 125 mounted in the bearing 126 and being pivoted at the lower end of each of its two arms to the rack bar rods 128; the usual adjustment means 129 being provided in 70 order to compensate for the slight wear of the shuttle hooks or the shuttle drivers and to insure the accurate positioning of the points of the shuttle hooks with respect to 75 the loops in the needle threads.

A novel and important point of difference between this machine and all previous ones is that in this machine, for the first time, the shuttles are mounted above the post, 80 permitting the use of the shaft of the presser foot as a partition wall to separate and to guide the shuttles in their oscillating movement. The partition walls 140 and 141 are each of the same thickness as the shaft 142 of the presser foot and serve to guide and support the presser foot in its forward and 85 downward movement.

The presser foot proper is a flat rectangular piece of metal 144 having a transverse slot 145 to receive the needles and is secured to the flat shaft 142, which is recessed as at 90 146 to conform to the configuration of the lower portion of the shuttle race horns 149 and is beveled as at 150 to permit convenient manipulation of the shuttle hooks as 95 they are inserted and removed from the arms 152 of the shuttle drivers.

The method of securing the shuttle hooks 100 within their respective races is of the usual type including a plurality of latch fingers 157 pivoted as at 158 and secured in place, when the shuttles are in position, by means of set screws 159 preferably having comparatively large knurled heads for rapid manipulation. The latches 157 are channeled out to 105 form a part of the race and the forwardly projecting horns 149 are also grooved for the same purpose, the latter, however, having but two walls with the race groove since 110 the presser foot shaft 142 and the partition 140 form the third or inner wall of the shuttle race.

The two latch members 157 are obviously 115 independently pivoted and while they bear against one another near their pivots they are separated as at 174 in Fig. 4 at their lower ends in order to permit reception between them of the cast-off of the needle thread, that is, the loop in the needle thread formed by the oscillation of the shuttle hooks. At the front end of the lower portion of the presser foot shaft 142 is a small but important element, the relatively sharp arcuate dividing guard 170, which not only 120 insures the correct spacing of the needles but cooperates with the proximate guard web 171 of the partition 27 to guard each of the thimble needles in case the fabric should be pulled, accidentally or otherwise, transversely to the line of seam.

Not only is the shaft 142 of the presser foot of material thickness so as to insure rigidity but it is supported at the top as it passes through the arm and at the bottom by its snug fit with the sturdy slotted race horns 149 so that there is no tendency for lateral movement of the presser foot and consequently the guiding guard 170 is always in exact registry with the corresponding cooperating guiding guard 171 of the partition in the post.

On top of the housing 10 is mounted a stationary shaft 180 on which is mounted a pair of sleeves 181 and 182 carrying respectively the rockers 183 and 184 each of which engages a cam on the main shaft 55. The rocker 184 is connected to the shaft 187 by means of a crank 188 and a rod 189 there being a slot and pivot connection 190 between the rod 189 and the upper arm 191 of the rocker 184 in order to assure accurate timing and to give minimum throw of the looper arms. This while perhaps of convenience is not at all essential as the timing and throw of the loopers are very rarely, if ever, modified on machines after once being set. The fork 194 secured to the shaft 187 and forming with the crank 188 a bell crank lever operates the cross arm loopers 196 and 197 by means of the toggle action 199, reversing the positions of the looper arms 196 and 197 at each movement, up or down, of the cross arm 200.

Particular attention is invited to the mechanism best seen in Fig. 2 by means of which the yoke 194 is operated once to each two revolutions of the main drive shaft 55; this movement being desired in order that the loopers may cross the stitch but once to each complete cycle of movement of the needles. A small pinion 202 fast to the main drive shaft 55 drives a gear 203 of twice the diameter imparting to the stub shaft 204 a half time revolution, this shaft carrying the cam 205 which drives the lower arm 207 of the rocker 184. At each revolution of the cam 205 the rod 189 is operated once forward and once backward; in other words, this connecting rod 189 and with it the fork 194 is operated in one direction only for each cycle of the needles and shuttles so that each of the two looper threads are thrown first to the right of the needles on one cycle of movement of the needle and shuttle mechanism and then to the left on the next cycle.

In addition to the movement of the looper arms 196 and 197 about their common pivot 209 these arms have a forward and backward movement in order alternately to clear the needles and to bring the looper threads or cover threads taut against the needles, such movement being imparted to the looper arms by means of the rocker 183 driven by the cam 210 which is connected to the crank

arm 212 fast to the rocker support 213 having a pivot 214 in each of the two brackets 216 extending slightly beyond the front face of the sewing machine arm 17.

This pivot block or support 213 carries the pivot 209 of the two looper arms 196 so that movement of the rocker 183 causes the substantially horizontal pivotal axis of the looper bars to oscillate about the center of the pivots 214 as an axis, which movement causes the tips of the two loopers to move forward of the two needles as the loopers cross one another in front of the needles and to recede behind, or at least on a line with, the needles as they are withdrawn into the post.

Referring now particularly to Fig. 19 the two needles are raised to their highest point and the two loopers have just moved to the limit of their backward throw so that the two looper threads 220 and 221 are taut against the needles 90 and 89, respectively, and remain in this position while the bight 222, caused in the first motion of retraction of the needles, is made into a loop in the usual way by the shuttle hooks so that as the take-up mechanism draws down the loops in the needle threads the looper threads 220 and 221 will be tightly held by the needle thread.

As the needles emerge from the post the loopers are spread wide apart and their tips are back of the line connecting the two twin needles, but as the needles penetrate the fabric a short distance the loopers start to move forwardly and simultaneously to cross one another. They complete their cross movement still in their forward position and then while spread apart move rearwardly as the points of the shuttle hooks engage the bights in the needle threads to form it into a loop. When the points of the shuttle hooks are still but a slight distance in front of the needles the loopers have completed their movement and remain quite stationary during the time the loop slips over the shuttle and do not start to reverse and to move forward until the shuttle hook points are again almost in line, but still a trifle forward of the two needles so that the two loopers bars cross each other only during the time when the shuttle hooks are behind the needles and the needles are at the extreme highest point of their travel.

The rock shaft 225 is journaled in the two side walls of the housing 10 and carries a pair of arms 226 and 227 forming a bell crank lever the arm 226 of which is a cam follower having the anti-friction roller 228 which engages the large cam 229 best seen at the right hand wall of the casing in Fig. 3, while the lower arm is the take-up being provided with a plurality of orifices 230 through which the needle threads pass as they extend from the tension 232 to the

guide-eye 233 on the plunger casing 102. When the shuttles are at their highest point the lower end of the take-up moves rapidly rearward in the usual manner drawing the 5 loop or cast-off in the needle thread down tight against the fabric in the well known manner, the take-up moving slowly forward as the needles rise to "give the needles thread" as usually expressed.

10 The needles threads 240 and 241 pass from the spools 13 and 14 passing through the thread guide 244 down through a second thread guide 245, to and through the two tubular thread guards 246 each of which is 15 slotted for convenient threading and thence through a hole 247 in the bed to the thimble 248 and from there the two needle threads separate, one passing to each of the two needle thread tension devices 232 after 20 which they are crossed over the central post 249 then passing to the take-up, each thread passing separately through one of the holders 230 in the take-up and again passing together through the eye or thread guard 25 233, then through the bore 88 of the needle unit and up along the groove 86 through the small eye 87 and thence to the needles 89 and 90. In actual practice no serious attempt is made to prevent the needle threads 30 240 and 241 from crossing one another in their travel since apparently the separation of the threads in their path, as previously mentioned, prevent any rubbing of the threads even though they should cross.

35 The bobbins are wound in the usual way and hence require no description. The looper threads 220 and 221 pass from the two spools 15 on opposite sides of the standard 12 and do not cross each other except at the 40 tips of the looper bars. From the spools these threads pass first from the spring wire guides 250 and then into the tension disks 251, then to the drop or balancing tensions 254, then to the wire thread guides 255, from 45 whence they pass to the eyes 257, here shown as three in number, on each looper arms, and finally through the central bore of the looper noses.

In order to insert the work, the hand lever 50 260, pivoted as at 261, and carrying at its upper end a cam 262, is pulled forward so that the cam engages an anti-friction roller 263 pivotally mounted on an arm on the shaft 142 of the presser foot, so as to raise 55 the presser foot against the tension of the leaf spring 265. The strength of this spring is governed in the usual way by the knurled fast set screw 266 in the pivoted stirrup 268 fastened to the arms 17. To lower the presser 60 foot against the work on the post the handle 260 is moved rearwardly which frees the cam from the roller 263 and places the movement of the presser foot entirely under the influence of the leaf spring 265.

What I claim is:

1. A post type sewing machine for closing the fingers of gloves of the type having a slender, vertical post to be received within a finger of a glove characterized by the combination of twin needles within the post and cooperating shuttle mechanisms above the post. 70

2. A post type sewing machine having a slender, vertical post of such size as to be received within a finger of a glove characterized by the provision of a needle, a feed, both within the post. 75

3. A post type sewing machine of the type having a slender, vertical post adapted to be received within a finger of a glove and employing a needle bar and a feed within said post, characterized by the provision of means whereby the feed guides the needle bar in its travel. 80

4. In a sewing machine of the type described, a slender, vertical post forming a work supporting member, a partition at the top of said member, a needle bar carrying a plurality of needles, said needle bar being entirely within the work supporting member and lying entirely forward of the plane of said partition. 85

5. A sewing machine of the post type in which the post is vertically slotted from top to bottom to facilitate the threading of the machine. 90

6. In a sewing machine of the type employing two shuttle mechanisms, a presser foot acting as a wall for the two shuttle mechanisms. 100

7. A sewing machine of the lock stitch type employing a plurality of shuttles characterized by the provision that each of the shuttles bears against the presser foot. 105

8. A sewing machine of the type having a slender, vertical post of such size as to be received within a finger of a glove and employing a plurality of needles and a presser foot on opposite sides of the goods to be sewed characterized by the provision of vertically elongated means movable with the presser foot to guide and separate the needles. 110

9. A sewing machine of the type employing a plurality of shuttle races and a presser foot, characterized by the presser foot being guided in its travel by portions of the shuttle races. 115

10. In a post type glove finger sewing machine, the combination of a slender, vertical work supporting post and a needle bar unit and feed mechanism within the post. 120

11. In a post type sewing machine, the combination of a slotted post and a grooved needle bar unit, the groove in the needle bar unit being proximate the slot in the post. 125

12. A sewing machine for closing the finger seams of gloves characterized by the

- provision of a reciprocating needle bar carrying needles at its top portion, and a pair of spaced means for guiding said bar in its reciprocation, one of said means being the feed and the other of said means being located beneath the bed of the machine.
13. In a post type sewing machine, a slender post, a vertical standard, a sleeve sliding on said standard, a reciprocating needle bar pivoted to said sleeve and extending into said post, and means within the post for guiding the needle end of said needle bar.
14. A sewing machine of the shuttle type characterized by the provision of a presser foot having a guiding bearing in the sewing machine arm and a second guiding bearing in the shuttle race.
15. A post type sewing machine for closing the finger seams of gloves and having a slender, vertical post of such size as to be received within a finger of a glove characterized by the provision of means within the post for feeding the work, and a needle bar also within the post and engaging said means.
16. A post type sewing machine for closing the finger seams of gloves and having a slender, vertical post of such size as to be received within a finger of a glove characterized by the provision of a feed member pivotally mounted within the post, and a needle also within said post.
17. In a sewing machine, a slender, vertical post, a needle within said post, a slotted feed bar within the post, a pivot for said feed bar, means for oscillating the feed bar about said pivot, and additional means for moving the feed bar upward during its oscillation.
18. A feed bar for a post type glove sewing machine characterized by the provision of two flat needle bar guiding faces arranged at an obtuse angle with one another.
19. In a post type glove sewing machine, a flange, a plurality of post sections fitting within said flange, and a partition bar joining the tops of the post sections.
20. In a post type glove sewing machine, a hollow post and a partition T-shaped in cross section at the top of the post for guiding and supporting the needles.
21. In a sewing machine, a presser foot characterized by the provision of a vertically disposed arcuate lip for guiding and supporting twin needles.
22. In a post type glove sewing machine having a slender, vertical post of such size as to be received within a finger of a glove characterized by the provision of needles supporting and guiding means within the post, and further needle separating and guiding means carried by the presser foot and cooperating with the means in the post.
23. A sewing machine having in combination an elongated work supporting post, a needle in the post, a feed mechanism in the post, and a shuttle opposite the needle.
24. A glove finger sewing machine having in combination a slender post for supporting the work, a needle in the post, feeding means in the post, and means cooperating with said needle and said feeding means to make lock-stitches.
25. In a sewing machine for closing the finger seams of gloves having in combination a narrow work supporting post, a needle, feed mechanism, and mechanism cooperating with said needle and said feed mechanism to make stitches, the feature of placing both the needle and feed mechanism within the post.
26. A sewing machine having in combination a post capable of supporting work, means within the post for reciprocating a plurality of needles into and out of the end of the post, means within the post for actuating feed devices in the end of the post and a plurality of shuttles cooperating with said needles.
27. A sewing machine having in combination a post, portions of which including the end thereof are capable of supporting work, means within the post for reciprocating a plurality of needles into and out of the end of the post, means within the post for actuating feed devices in the end of the post and a plurality of shuttles cooperating with said needles and a presser foot cooperating with said feed devices.
28. A machine for sewing blanks to form tubes in such a manner that at each seam one edge will be inside the tube and the other edge outside having in combination a post not larger than the closed tube, means within the post for reciprocating a plurality of needles into and out of the end of the post, means within the post for actuating feed devices in the end of the post and a plurality of shuttles cooperating with said needles.
29. A machine for sewing blanks to form tubes in such a manner that at each seam one edge will be inside the tube and the other edge outside having in combination a post which approximates the size of the closed tubes so that in guiding the blank for the last or closing seam the edges to form this seam can be overlapped on the post, means within the post for reciprocating a plurality of needles into and out of the end of the post, means within the post for actuating feed devices in the end of the post and a plurality of shuttles cooperating with said needles.
30. A machine for sewing blanks to form tubes in such a manner that at each seam one edge will be inside the tube and the other edge outside having in combination a post which approximates the size of the closed

tubes, a continuous guiding surface formed out of the top end and the front side of said post which surface is flat except where it passes from the front to the top of the post so that in guiding the blank for the last or closing seam the edges to form this seam can be overlapped on the post and held on the flat guiding surface a consider-

able distance ahead of the needles, means within the post for reciprocating a plurality of needles into and out of the end of the post, means within the post for actuating feed devices in the end of the post and additional cooperating mechanism to form a series of stitches.

CLARENCE H. WILKES.
